UNITED STATES PATENT OFFICE.

OTTO MEHRTENS, OF KIEL, GERMANY, ASSIGNOR TO FRIED. KRUPP AKTIENGESELLSCHAFT
GERMANIAWERFT, OF KIEL-GAARDEN, GERMANY.

TRANSPORT VESSEL.

No. 886,621.

Specification of Letters Patent.

Patented May 5, 1908.

Application filed April 9, 1906. Serial No. 310,801.

To all whom it may concern:

Be it known that I, OTTO MEHRTENS, a subject of the Emperor of Germany, and a resident of Kiel, Germany, have invented 5 certain new and useful Improvements in Transport Vessels, of which the following is a specification.

The present invention relates to vessels for carrying cargo in bulk such as coal, grain and 10 the like. In the construction of such vessels, ship owners prescribe the following conditions, among others: 1. The vessel must be self-trimming, that is to say, the filling of the cargo-spaces must, as far as possible, take 15 place automatically without any considerable stowing work; any gaps left unfilled or developing from the settling and joiting together of the cargo must be such that they can fill automatically from the material in 20 the hatches and in the superstructure by the movements of the vessel at sea, without interfering with the stability of the vessel. 2. The stability of the vessel must be good, that 25 is to say, the rolling period of the vessel must not be too short. 3. The vessel must be capable of holding such an amount of water ballast that the propeller will be completely submerged when the vessel is light.

It has been suggested to comply with the 30 above-mentioned requirements by constructing the side walls of the holds with an angle of inclination to the horizontal plane, corresponding to the angle of rake or slope of the cargo and by securing the water ballast 35 through special ballast tanks on or below the deck, in addition to the customary double bottom. According to the system of measurement adopted by most nations for determining the tonnage of sea-going vessels, only 40 the ballast-space inclosed by the double walls of the hull, is free of tax, while the remaining ballast-spaces, such as deck-tanks and side tanks, are reckoned in the measurement for tonnage and are, therefore, not exempt in the 45 assessment of dock, harbor, canal, and other dues, charges for towage, etc. Hence transport or cargo vessels constructed as above-outlined are disadvantageous as far as the taxable or assessable space is concerned.

50 The object of the present invention is to provide a transport-vessel, which comes up to standard requirements, and which, moreover combines a maximum of bulk capacity and tonnage with a minimum of taxable or 55 assessable space.

A transport vessel embodying the present invention is shown diagrammatically in the accompanying drawing, in which:

Figure 1 is a cross-section of the vessel, taken in a plane near one of the hatches, and 60 Fig. 2 is a cross-section taken through or adjacent to the bridge.

The vessel is provided with a double hull, 65 A, B, which is continued not only throughout the bottom as in ships heretofore constructed, but extends up to the harbor-deck C on both sides. The space between the walls A and B is adapted to receive water ballast and is divided by means of longitudinal partitions D into compartments which 70 may communicate with one another in any suitable manner. The harbor-deck is 75 surmounted by a sea-proof superstructure E, e', extending throughout the length of the vessel and having its side-walls e' extending upwardly directly from the inner wall B of the hull and at an angle of inclination to the horizontal plane, approximately corresponding to the rake or slope of the cargo. The side walls of the hold are free from projections or irregularities so as to be perfectly smooth. On the superstructure are 80 arranged hatches F (Fig. 1) and the customary projecting parts such as the smoke-stack G and the bridge H (Fig. 2).

85 It will be easily understood that a vessel constructed according to the present invention complies with the standard requirements of construction, the self-trimming property being obtained through the arrangement of the superstructure and the hatches as also through the inclined side walls e' of the superstructure and the smooth side walls of the hold, while the regulation of the stability and of the draft is attained 90 through the introduction of a sufficient amount of water ballast into the double hull which extends clear up to the harbor-deck.

95 Since in my improved vessel the entire water ballast is placed in the double-hull extending up to the harbor-deck the entire ballast space, contrary to known ship-constructions, is free of assessment, according to the international system of tonnage measurement for sea-going vessels.

100 Besides the advantage of a low measurement, other advantages accrue from the presence of the sea-proof superstructure. According to the practice followed by classification companies (surveyors), a smaller 105

110

free-board (the perpendicular distance between the draft-line and the edge of the sheer-plank, amidships) is allowed in vessels having a continuous sea-proof superstructure than in vessels without such a structure. A greater draft of the vessel is, therefore, permitted, and a larger loading capacity of the vessel obtained. Furthermore, the practice of these companies, as far as the strength of material (plating and the like) is concerned, permits of the vessel being lighter when it has a continuous sea-proof superstructure.

A vessel equipped in accordance with the present invention has, with a very slight measurement and a large loading capacity, a comparatively small intrinsic weight (net displacement) and consequently a comparatively large carrying capacity.

The firmness of the hull of the vessel is increased and the danger of leakage decreased by having the double-hull continued clear up to the harbor-deck. Furthermore, by placing the water ballast in the continuous double hull A, B, a better protection of the hull is obtained than is the case in vessels having separate water ballast tanks. In practice, suitable means will be embodied

for introducing and withdrawing water ballast at will.

What I claim is:

1. A transport vessel having a double hull extending throughout the bottom and up to the harbor deck, and a sea-proof superstructure surmounting the harbor deck and having side walls extending directly from the inner wall of the hull and inclined to the horizontal at an angle approximately corresponding to the rake or slope of the cargo. 30

2. A transport vessel having a double hull extending throughout the bottom and up to the harbor-deck, and a sea-proof superstructure extending throughout the length of the vessel, surmounting the harbor-deck, and constructed with side walls inclined to the horizontal, at an angle approximately corresponding to the rake or slope of the cargo 40

The side walls of the super-structure extending directly from the inner wall of the hull.

The foregoing specification signed at Kiel this 12th day of March, 1906.

OTTO MEHRTENS.

In presence of—

JULIUS RÖPKE,
C. W. KRÜTZFIELD.
